UNITED STATES PATENT OFFICE.

FREDERICK HELLER, OF NEWARK, NEW JERSEY.

JEWELRY NOVELTY.

1,272,257.

Specification of Letters Patent.

Patented July 9, 1918.

Application filed March 16, 1916. Serial No. 84,577.

To all whom it may concern:

Be it known that I, FREDERICK HELLER, a citizen of the United States of America, resident of Newark, State of New Jersey, have 5 invented certain new and useful Improvements in Jewelry Novelties, of which the following is a specification.

The present invention relates to improvements in jewelry novelties, and particularly 10 as one embodiment a flexible bracelet having the appearance of a solid or continuous bracelet. It is an object of the invention to provide such a jewelry novelty which will possess both exteriorly and interiorly, a 15 smooth and finished appearance, which because of its flexibility will naturally assume graceful lines, and at the same time will in no way be suggestive of the mechanical means employed for bringing about these 20 advantageous features. Another object is to provide such a jewelry novelty which will be strong, simple to manufacture, seamless and solderless, and highly resistant to wear.

With these and other objects in view, my 25 invention is shown in the accompanying drawings, and will be hereinafter more fully described with reference thereto, and finally pointed out in the claim.

In the drawings—

30 Figure 1 is a perspective view of one embodiment, as for instance, a bracelet made according to my invention,

Fig. 2 is a perspective view of one of the chain units,

35 Fig. 3 is a perspective view of one of the outer or cover units,

Fig. 4 is a plan view of a portion of the bracelet,

Fig. 5 is a side view thereof,

40 Fig. 6 shows the bracelet in process of assembling, and

Fig. 7 is a sectional view of a modified form of cover unit.

Similar reference characters indicate corresponding parts throughout the several figures of the drawings.

Referring to the drawings, my improved bracelet comprises a plurality of chain units, 10 and outer or cover units 11, which fit 50 respectively over each chain unit. The chain units are U-shaped, consisting of side portions 12, and 13, the reduced connecting portion 14 and reduced inturned ends 15 and 16 at the end of the side portions. Adjacent 55 the connecting portion 14 the side portions are bent inwardly as at 17 and 18, so that a

recess is provided at each end of a depth corresponding substantially to the thickness of the metal. Openings 19 and 20 are provided respectively in the said portions 17 60 and 18, of sufficient size to accommodate the inturned ends 15 and 16 of the next adjacent unit. The upper edges of the side portions are carried downwardly to the front face of the inturned end as at 21 and 65 22, and the under edges are recessed as at 23 and 24, to permit of hinged movement of the parts inwardly, as hereinafter pointed out. The metal is preferably slightly springy, and the unassembled side portions flare out- 70 wardly as clearly shown in Figs. 2 and 6.

The cover members 11 are preferably 75 seamless, being formed from tubular metal, and are rectangular in cross-section. One end thereof is convex as at 25, and the opposite end is concave as at 26. This concavity extends from the upper outer surface to the lower inner surface, so that the edge 27 of the lower wall is straight, as clearly indicated in Fig. 3.

80 There is a slight difference in the length of the chain and cover units, sufficient to allow for the connecting of the chain units.

The bracelet is assembled as shown in Fig. 6 the cover units being slid over the 85 chain units, forcing the inturned ends 15 and 16 of one unit into the openings 19 and 20 of the adjacent unit. There is a substantially snug fit between the chain and cover units, and by reason of the springiness of 90 the chain units, there is sufficient friction between the parts to hold the same in proper position with respect to each other. The convex end of each cover member extends over the connection between the chain units, 95 and fits the concave end of the next member. The straight edge 27 and the recesses 23 and 24 permit movement of the sections in one direction sufficient to form a flexible ring. In the other direction the movement 100 is more restricted as it is not desirable to bend the bracelet in this way. The outer surface by reason of the close fitting of the concave and convex ends, presents a substantially continuous appearance. The end sections 30 and 31 are suitably secured, preferably by soldering, and are provided with a catch device 32 in the usual manner.

105 Instead of the straight edge 27, a tapered edge 33 may be provided as shown in Fig. 7, 110 which is rounded by the same tool which rounds out the concavity. The cover unit

is preferably seamless, being formed from tube metal, but it may if desirable be formed in halves soldered together.

With my improvements it will be seen a bracelet of great artistic beauty is produced, without any suggestion of the mechanical means employed for bringing about the various features which lend to its desirability for the use intended.

10 My improvements may take the form of watch fobs, chains, hairdles for vanity cases, and similar other uses wherein chain-like constructions find adaptation.

I have illustrated a preferred and satisfactory form of my invention, but it is obvious that changes may be made therein, within the spirit and scope thereof, as defined in the appended claim.

I claim:

20 A device of the character described, comprising a plurality of chain units, hingedly

connected together, and provided respectively at one end, and at their under sides with recessed portions; a plurality of sleeve units inclosing respectively each of said chain units, adjacent portions of said sleeve units adapted to remain in contact during movement of the units with respect to each other; and to cover the hinge connections between the chain units, the lower side of 25 said sleeve units being provided at one end with a straight wall adapted to cooperate with said recessed portions of said chain units to permit greater hinged movement in one direction than the other.

In testimony that I claim the foregoing as my invention, I have signed my name in the presence of two subscribing witnesses.

FREDERICK HELLER.
